UNITED STATES PATENT OFFICE.

MATTHEW SMITH MOORE, OF GLASGOW, SCOTLAND, ASSIGNOR TO MAVOR & COULSON, LIMITED, OF GLASGOW, SCOTLAND.

CUTTER-CHAIN MINING-MACHINE.

1,368,521.

Specification of Letters Patent. Patented Feb. 15, 1921.

Application filed January 20, 1920. Serial No. 352,889.

To all whom it may concern:

Be it known that I, MATTHEW SMITH MOORE, a subject of the King of Great Britain and Ireland, of 47 Broad street, Mile End, Glasgow, Scotland, have invented new and useful Improvements in or Connected with Cutter-Chain Mining-Machines for Use in Mining Coal and other Minerals, of which the following is a specification.

10 This invention refers to improvements in or connected with cutter chain machines particularly adapted for use in mining coal and other minerals, of the type comprising a body part furnished with a motor and 15 provided with a gear casing at the head of the body part from which there extends a cutter chain member mounted capable of angular adjustment about an axis at right angles to the plane of the cutter chain member, and in which the cutter chain thereof is driven by a sprocket wheel to which rotation is imparted through gearing contained within the gear casing by power derived from the motor in driving connection with 20 a power shaft which extends into the gear casing.

To simplify explanations in the description and the claims it will be assumed that the machines each occupy a position in 30 which the cutter chain is situated below the gear casing and that the plane of the cutter chain is horizontal for performing undercutting operations.

Machines according to this invention comprise a gear casing formed with an internal circular channel at its base the axis of which channel is vertical, which gear casing is divided transversely in a plane containing the axis of the channel and at right angles or 40 thereabout to the power shaft of the motor, one part of the gear casing being permanently fixed to the body of the machine and the other part adapted to be detachably secured to the fixed part, a base structure having a circular rim adapted to be mounted with its rim fitting within the channel of the gear casing, a chain driving sprocket wheel located below the base structure mounted upon a driving axle extending 45 through the base structure, and a cutter chain member, the plane of which is below the base structure, mounted capable of angular adjustment about a vertical axis situated in the area contained within the circumference of the base structure.

In machines according to this invention the cutter chain member may be mounted capable of angular adjustment either about the vertical axis of the base structure or about a vertical axis situated between the center of the base structure and circumference thereof, and in both of these cases the chain driving sprocket wheel may be mounted co-axial with the axis about which the cutter chain member is mounted capable of angular adjustment, and in the first case the sprocket wheel may be otherwise mounted about an axis situated between the center of the base structure and circumference thereof to which axis the movements of angular adjustments are imparted. In some arrangements the base structure and the cutter chain member are associated to turn angularly together, in which case the rim of the base structure is mounted capable of angular movement in the internal channel of the gear casing, and in other arrangements the base structure is fixed against angular movement in the channel of the gear casing, in which case the cutter chain member is mounted capable of angular adjustment about the axis of the base structure or about an axis located between the center of the base structure and rim thereof.

Some examples of construction according to this invention will now be described with reference to the accompanying drawings, in which:—

Figure 1 is a plan of a cutter chain machine. Figs. 2, 3, 4 and 5 are longitudinal vertical sections, each illustrating a construction to be described.

In the drawings A designates the body of the machine, B the motor, an electric motor for example, C the fixed part and C¹ the detachable part of the gear casing, D the internal channel formed at the base of the gear casing, E the base structure, F the cutter chain member, G the cutter chain, H the chain driving sprocket wheel, and K the power shaft of the motor.

In the constructions illustrated at Figs. 2 and 3 the base structure E and cutter chain member F are associated to turn angularly together about the axis of the base structure E, the rim of the base structure E being mounted capable of angular movement in the internal channel D of the gear casing. In Fig. 2 the chain driving sprocket wheel H, which is mounted co-axial with the base

structure E, is axially connected to rotate with a bevel gear wheel L driven by a bevel pinion M provided on the power shaft K of the motor. In Fig. 3 the chain driving 5 sprocket wheel H, which is mounted to rotate about an axis located between the center of the base structure E and circumference thereof, is axially connected to rotate with a toothed wheel N in gear with a pinion P which is axially connected to rotate 10 with the bevel gear wheel L driven by the bevel pinion M.

In the constructions illustrated at Figs. 4 and 5 the base structure E is held stationary 15 relative to the gear casing, the rim of the base structure E being fixed against angular movement in the channel D. In Fig. 4 the chain driving sprocket wheel H is mounted co-axially with the base structure E, and in Fig. 5 the sprocket wheel H is mounted to 20 rotate about an axis located between the center of the base structure E and circumference thereof, and in each case the cutter chain member F is arranged capable of 25 angular adjustment about the axis of the sprocket wheel H by being mounted on a circular sleeve R projecting from the under-side of the base E co-axial with the sprocket H. In Fig. 4 the sprocket wheel H is axially 30 connected to rotate with the bevel gear wheel L driven by the bevel pinion M, and in Fig. 5 the sprocket wheel H is axially connected to 35 rotate with the toothed wheel N in gear with the pinion P which is axially connected to rotate with the bevel wheel L driven by the bevel pinion M.

It will be recognized that the base structure E is required to be placed in position with one half of the circumference of its 40 rim fitting within the portion of the channel D formed in the fixed part C of the gear casing before the detachable part C¹ of the gear casing is applied and secured to the fixed part C, and in order to remove the 45 base structure E the part C¹ of the gear casing has first to be detached.

I claim.

1. A cutter chain machine comprising a body part, a motor, a gear casing at the head 50 of the body part, a power shaft in driven connection with the motor extending into the gear casing, an internal circular channel formed at the base of the gear casing the axis of which channel is vertical, said gear casing being divided transversely in a plane containing the axis of the channel and at right angles or thereabout to the power shaft of the motor, one part of the gear casing being permanently fixed to the body of the 55 machine, and the other part adapted to be detachably secured to the fixed part, a base structure having a circular rim adapted to be mounted with its rim fitting within the channel of the gear casing, a chain driving 60 sprocket wheel located below the base structure mounted upon a driving axle extending through the base structure said driving axle being situated between the center of the base structure and circumference thereof, gearing for driving the sprocket wheel from the power shaft, and a cutter chain member below the base structure mounted capable of angular adjustment about a vertical axis situated in the area contained 65 within the circumference of the base structure.

ture mounted upon a driving axle extending through the base structure, gearing for driving the sprocket wheel from the power shaft, and a cutter chain member below the base structure mounted capable of angular adjustment about a vertical axis situated in the area contained within the circumference of the base structure. 70

2. A cutter chain machine comprising a body part, a motor, a gear casing at the head 75 of the body part, a power shaft in driven connection with the motor extending into the gear casing, an internal circular channel formed at the base of the gear casing the axis of which channel is vertical, said gear casing being divided transversely in a plane containing the axis of the channel and at right angles or thereabout to the power shaft of the motor, one part of the gear casing being permanently fixed to the body of the 80 machine and the other part adapted to be detachably secured to the fixed part, a base structure having a circular rim adapted to be mounted with its rim fitting within the channel of the gear casing, a chain driving sprocket wheel located below the base structure mounted upon a driving axle extending through the base structure, gearing for driving 85 the sprocket wheel from the power shaft, and a cutter chain member below the base structure mounted capable of angular adjustment about the vertical axis of the base structure. 90

3. A cutter chain machine comprising a body part, a motor, a gear casing at the head 100 of the body part, a power shaft in driven connection with the motor extending into the gear casing, an internal circular channel formed at the base of the gear casing the axis of which channel is vertical, said gear casing being divided transversely in a plane containing the axis of the channel and at right angles or thereabout to the power shaft of the motor, one part of the gear casing being 105 permanently fixed to the body of the machine and the other part adapted to be detachably secured to the fixed part, a base structure having a circular rim adapted to be mounted with its rim fitting within the channel of the gear casing, a chain driving sprocket wheel located below the base structure mounted upon a driving axle extending through the base structure said driving 110 axle being situated between the center of the base structure and circumference thereof, gearing for driving the sprocket wheel from the power shaft, and a cutter chain member below the base structure mounted capable of angular adjustment about a vertical axis situated in the area contained 115 within the circumference of the base structure.

4. A cutter chain machine comprising a body part, a motor, a gear casing at the head of the body part, a power shaft in 120 driven connection with the motor extending into the gear casing, an internal circular channel formed at the base of the gear casing the axis of which channel is vertical, said gear casing being divided transversely in a plane containing the axis of the channel and at right angles or thereabout to the power shaft of the motor, one part of the gear casing being permanently fixed to the body of the machine, and the other part adapted to be detachably secured to the fixed part, a base structure having a circular rim adapted to be mounted with its rim fitting within the channel of the gear casing, a chain driving sprocket wheel located below the base structure mounted upon a driving axle extending through the base structure said driving 125 axle being situated between the center of the base structure and circumference thereof, gearing for driving the sprocket wheel from the power shaft, and a cutter chain member below the base structure mounted capable of angular adjustment about a vertical axis situated in the area contained within the circumference of the base structure. 130

driven connection with the motor extending into the gear casing, an internal circular channel formed at the base of the gear casing the axis of which channel is vertical, 5 said gear casing being divided transversely in a plane containing the axis of the channel and at right angles or thereabout to the power shaft of the motor, one part of the gear casing being permanently fixed to the 10 body of the machine and the other part adapted to be detachably secured to the fixed part, a base structure having a circular rim adapted to be mounted with its rim fitting within the channel of the gear casing and capable of angular movement therein, a chain driving sprocket wheel located 15 below the base structure mounted upon a driving axle extending through the base structure, said driving axle being situated 20 between the center of the base structure and circumference thereof, gearing for driving the sprocket wheel from the power shaft, and a cutter chain member below the base structure mounted capable of angular adjustment with the base structure about the 25 vertical axis thereof.

5. A cutter chain machine comprising a body part, a motor, a gear casing at the head of the body part, a power shaft in 30 driven connection with the motor extending into the gear casing, an internal circular channel formed at the base of the gear casing the axis of which channel is vertical, said gear casing being divided transversely in a 35 plane containing the axis of the channel and at right angles or thereabout to the power shaft of the motor, one part of the gear casing being permanently fixed to the body of the machine and the other part adapted to 40 be detachably secured to the fixed part, a base structure having a circular rim adapted to be mounted with its rim fitting within the channel of the gear casing, a chain driving sprocket wheel located below the base 45 structure mounted upon a driving axle extending through the base structure, said driving axle being situated between the cen-

ter of the base structure and circumference thereof, a toothed wheel connected to rotate with the driving axle of the sprocket 50 wheel, a pinion mounted to rotate about the axis of the base structure in gear with said toothed wheel, a gear wheel axially connected to rotate with said pinion, a driving pinion on the power shaft in mesh with said 55 gear wheel, and a cutter chain member below the base structure mounted capable of angular adjustment about a vertical axis situated in the area contained within the circumference of the base structure. 60

6. A cutter chain machine comprising a body part, a motor, a gear casing at the head of the body part, a power shaft in driven connection with the motor extending into the gear casing, an internal circular channel formed at the base of the gear casing the axis of which channel is vertical, said gear casing being divided transversely in a plane containing the axis of the channel and at right angles or thereabout to the power 70 shaft of the motor, one part of the gear casing being permanently fixed to the body of the machine and the other part adapted to be detachably secured to the fixed part, a base structure having a circular rim adapted 75 to be mounted with its rim fitting within the channel of the gear casing, a chain driving sprocket wheel located below the base structure mounted upon a driving axle extending through the base structure, said driving axle being situated between the center of the base structure and circumference thereof, a toothed wheel connected to rotate with the driving axle of the sprocket wheel, a pinion mounted to rotate about the axis 80 of the base structure in gear with said toothed wheel, a gear wheel axially connected to rotate with said pinion, a driving pinion on the power shaft in mesh with said 85 gear wheel, and a cutter chain member below the base structure, mounted capable of angular adjustment about the vertical axis 90 of the base structure,

MATTHEW SMITH MOORE.
